UNITED STATES PATENT OFFICE.

MORRIS J. BAILEY, OF WINTHROP, MASSACHUSETTS.

EXTENSION DELIVERY MECHANISM.

Application filed March 5, 1923. Serial No. 622,793.

To all whom it may concern:

Be it known that I, MORRIS J. BAILEY, a citizen of the United States, and a resident of Winthrop, in the county of Suffolk and State of Massachusetts, have invented an Improvement in Extension Delivery Mechanism, of which the following description, in connection with the accompanying drawings, is a specification, like letters on the drawings representing like parts.

My present invention relates to printing presses, and more particularly to an improved extension delivery or piling table for printing presses and the like.

In printing presses it is frequently desirable, and sometimes necessary, to provide means whereby the printed sheets delivered from the press are arranged in piled relation to each other at a considerable distance from the delivery end of the press, this being frequently desirable and necessary when slow drying ink, or a great deal of ink, is placed on the sheets. The distance between the delivery end of the printing press and the place where the sheets are piled being in this instance relatively distant from each other, the ink has a chance to dry sufficiently to allow the sheets to be piled one on the other without the interposition of a drying sheet, which is necessary where an extension delivery or piling table is not employed. Heretofore piling tables have formed practically an integral part of the press with which they were associated and it was necessary, therefore, to provide additional floor space for such press in addition to the already large space taken up by the press proper and, as it was not feasible or necessary to provide each press in a battery of presses with an extension piling table, those presses that were provided with piling tables encroached on the floor space provided at the delivery end of all the presses with the effect that access to the various presses with trucks, paper, etc., was seriously impeded. In some of the extension piling tables for printing presses it was attempted to bridge the gap between the delivery end of the presses and the entrance end of the extension piling table with mechanism over which the printed sheet was transported and when such extension

piling table was not in use, the bridging elements were swung up out of the way. The piling table, however, represents a considerable investment, and it was not in the interest of economy or good management to allow such table to lie idle, which it must necessarily do when the piling table formed practically a portion of the press with which it was associated.

In my present invention I have avoided the objectionable features of prior inventions along this line and have devised an extension delivery or piling table for printing presses which is relatively light in character and which, when not in use by one press, may be readily moved to any other press and associated with such other press to perform its function. In this manner, therefore, I have found that a small number of extension delivery or piling tables is sufficient to serve a relatively large number of presses and such extension delivery or piling tables are economically employed because they are employed a major portion of the time.

In carrying out my improved invention, I provide a platform or table running on castors or wheels and which table is provided with mechanism for attaching it temporarily to the delivery end of a press and with means for temporarily connecting the working parts thereof to the working parts of the delivery mechanism of the press and with means for automatically lowering the paper holding shelf or table as the sheets are piled up thereon, thereby maintaining the top of the pile at a substantially uniform height. Another improvement of my invention resides in the means for suspending the sheet supporting means so as to readily deposit the piled up sheets in position to be moved from the extension delivery or piling table by a truck with a minimum amount of handling.

Various other features and novel constructions will appear as the description of the invention progresses.

In the accompanying drawings illustrating the preferred embodiments of my invention,

Fig. 1 is a plan view;

Fig. 2 is a central sectional elevation on the line 2—2 of Fig. 1;

Fig. 3 is a central sectional side elevation on the line 3—3 of Fig. 1;

5 Fig. 4 is a left side elevation;

Fig. 5 is a right side elevation;

Fig. 6 is an enlarged detail sectional side elevation of a portion of the device;

Fig. 7 is a side elevation of a portion of 10 the machine showing the automatic lowering device for the paper holding table, and

Fig. 8 is a sectional side elevation of an alternative delivery scheme.

Referring to the drawings, 10 and 11 designate side and end members, respectively, tied together at their ends to the upper ends of legs 12 in any suitable manner, brackets 13 and 14 being employed to brace the members 10, 11, and 12 together. The lower ends 20 of the legs 12 are provided with bolts 15 working in a slot 16 arranged vertically in a member 17, which member 17 is provided with a bearing 18 on its bottom end in which is rotatably mounted a pulley or castor 19, as clearly shown in Fig. 8, the bolts 15 and slot 16 enabling the legs 12 and members 17 to be moved lengthwise with respect to each other to raise or lower the frame comprised of the members 10 and 11 respectively.

25 30 Mounted on the upper surface of the side members 10 and spaced along the length thereof are bearing blocks 20 in which blocks are rotatably mounted a shaft 21, there being one such shaft for each of the side members 10 and the shafts 21 are therefore arranged parallel to each other. Secured to each of the shafts 21 is a pair of sprocket wheels 22 over each of which runs a sprocket chain 23, one end of each of which has

40 attached thereto a weight 24 while the other end is attached to a cross frame consisting of a pair of bars 25. Secured to the end member 11 on the front of the device and at each end thereof are bearing brackets 26 in

45 which is rotatably mounted a shaft 27 provided at each end with a worm 28 which meshes with, and drives, a worm wheel 29 secured to the front end of the shaft 21. The crank handle 30 mounted on one end of

50 the shaft 27 provides means by which the shaft may be rotated and therefore the shafts 21 rotated in the same direction and in unison to raise or lower the framework suspended from the sprocket chains 23.

55 Means to be hereinafter described is provided for intermittently and automatically rotating the shaft 27 to automatically lower the frame consisting of the members 25.

Secured to the top surface of each of the 60 side members 11 and on the inner edge thereof is a strip 31 on each of which is mounted, for reciprocation, a crosshead 32, the two cross-heads 32 being secured to each other and spaced apart by a channel iron 33, the usual bolts 34 being employed to se-

cure the members together. The cross-heads 32 have formed integrally therewith and extending upwardly therefrom bars 35 at the upper ends of which are formed extensions 36 each provided with a lined bearings in which are rotatably mounted the parallelly arranged shafts 37 and 38 respectively. The shaft 37 has secured thereto at intervals and extending rearwardly toward the printing press a plurality of gripping members 39 which are associated with corresponding gripping members 40 secured at like intervals to the shaft 38, light springs 41 having their ends secured to the members 39 and 40 respectively and which 70 springs tend to urge such gripping members together. Secured to the rear end of the left hand side member 10 by screws 42 is a member 43 in which is pivotally mounted a ratchet tooth 44, a light spring 45 having 75 its ends attached to the outer free end of the ratchet tooth 44 and the member 43 respectively, a pin 46 limiting the movement to the left, as viewed in Fig. 4, of the outer free end of such ratchet tooth 44. Secured to the left hand end of the shaft 37 is a cam lever 47 which, as the crossheads 32 move to the rear of the apparatus, rides up on the cam tooth 46 causing a rotation of the shaft 37 to move the gripping members 80 39 upward away from the gripping members 40 thereby bringing such gripping members into position to grasp the forward edge of the paper as it is fed out from the press. Secured to the extreme front end of 85 the right hand member 10 by screws 48 is a cam block 49, the cam surface of which lies in the path of movement of a roller 50 mounted on the end of a lever 51 that is secured to the extreme right hand end of the 90 shaft 38 and, as the crossheads 32 with their associated elements move to the front or to the left, as viewed in Fig. 5, the roller 50 riding up on the cam surface of the cam block 49 will cause a rotation of the shaft 95 38 to move the gripping members 40 downward from engagement with the gripping members 39, thereby releasing the paper that may have been gripped therebetween. Secured to the shaft 38 at any convenient 100 point along the length thereof by a bolt 52 is a collar 53 to which is secured an arm 54 that engages with the shaft 38 and limits the rotative movement of the shaft 37 in a direction to bring the gripping members 39 105 and 40 into close association while secured to the shaft 38 and at any convenient point along the length thereof by bolt 55 is a collar 56 to which is secured the arm 57 which 110 engages with the shaft 37 to prevent rotative movement of the shaft 38 in a direction to bring the gripping member 40 into close association with the gripping member 39. Temporarily secured to the end members 11 115 by any suitable form of clamping means are 120

125 130

T-shaped members 58, the forward ends of which terminate adjacent the forward end of the device while the rearward ends extend well to the rear of the rearmost end 5 member 11, as shown in Fig. 1. This form of attachment of the members 58 to the end members 11 is to enable the members 58 and parts carried thereby to be adjusted toward and from each other so as to be able to accommodate the elements carried thereby to any width of press. Secured to each end of each of the T-shaped members 58 by bolts 59 is a shaft 60 on each of which is rotatably mounted a pulley 61 and over the pulleys 61 10 of each pair of pulleys on each of the T-shaped members 58 runs a belt 62, the ends of these belts being provided with devices 63 by means of which they are connected to the cross bar 33 that is secured at its ends to 15 the crossheads 32.

The press proper is provided on each side of the forward end with a bar 64. Arranged parallel to, but beneath, each of the bars 64 are bars 65 and extending between the bars 65 at the forward end thereof is a roller 66 over which extends a plurality of parallelly arranged conveying tapes 67, as is usual in this form of press. Secured to the forward ends of the bars 65 by screws 68 and extending upwardly therefrom are crossheads 69 each of which is provided with an outwardly extending roller 70 that rests on the top surface of the bars 64. Pivottally mounted to each of the crossheads 69 is the forward end 30 of a bar 71 constituting the delivery mechanism of the press. Reciprocation of the delivery mechanism 71 causes a rearward and forward reciprocating movement of the crossheads 69 and all parts attached thereto, 35 in this manner carrying the printed paper as it is delivered from the press forward on the tape 67 where, were no extension delivery provided, the mechanism would deliver the printed paper in the position in which the tapes 67 are shown in Fig. 1. Secured to the forward end of the members 65 is a device 40 45 50 55 60 65 70 75 80 85 90 95 100 105 110 115 120 125 130 135 140 145 150 155 160 165 170 175 180 185 190 195 200 205 210 215 220 225 230 Secured to the under side of the cross bar 33 near each end thereof and extending rearwardly therefrom is a bar 75 and on the forward ends of each of these is rotatably mounted a spring roller 76 to which is secured, at suitably spaced intervals, one end of tapes 77, the other ends of these tapes being secured to the rear end member 11 by block 78, as clearly shown in Fig. 6. On the rear end of the T-shaped members 58 and on the top edges thereof is rotatably mounted a shaft 79 provided intermediate its ends with a plurality of jogging devices 80 and at its extreme ends with bell crank

levers, one arm 81 of which is in alinement with, and of the same length thereof, as the jogging devices 80 and its other arm 82 is forked to straddle a shaft or rod 83 slidably mounted in bearings 84 formed on, or secured to, the side of the T-shaped members 58. The rods or bars 83 are provided with spaced nuts 85 the distance between which may be varied to control the length of throw of the jogging arm 81 and the jogging devices 80 and to the free end of the arm 82 is secured one end of a coil spring 86, the other end of this coil spring being secured to the T-shaped member 58 at any desirable point, and the function of this spring is to urge the free end of the arm 82 to the right, as viewed in Fig. 6, and therefore urge the free end of the arm 81 and the jogging devices 80 to the left, as viewed in the figure. The effect of this construction is to urge or kick the sheet of paper 87 forward with a positive movement into position where the engagement of such sheet by the gripping devices 39 and 40 will be insured. Secured to the members 69 and extending therebetween is a shaft 88 provided with a plurality of spring fingers 89 whereby it is insured that the extreme forward edge of the sheet will be in position to enter the space between the gripping devices 39 and 40.

Resting on the cross beams 25 is a block or platform top 90 on which is fed the sheets of paper 87. In order to pile this paper uniformly, I have arranged on the inner side of the cross members 10 a light framework 91, preferably of wood, and on two sides of this framework I arrange jogging frames comprising on the rear side a right angled shaft member 92 provided with diagonal slots 93 through which extends pins 94 secured on the framework 91. Light springs 95 connect the framework 91 and the right angled member 92. This right angled member 92 is also provided with a pivoted arm 96 spring held by means of a spring 97 against the pin 98 and this arm 96 lies in the path of movement of a pin 99 secured to the under side of a cross bar or frame 33. The jogging member on the side of the device consists essentially of a right angled member 100 provided with a plurality of diagonal slots 101 through which pass pins 102 secured to the light framework 91 and the upper face of the right angled member 100 is provided with a stop 103. A light spring 104 connects the right angled member 100 to the light framework 91. The stop 103 lies in the path of movement of a pin 105 secured to the under side of the cross bar or frame 33. From the above, it is evident that, as the cross bar or frame 33 reciprocates, the pin 99 will strike the arm 96 moving the right angled member 92 forward and upward, as viewed in Fig. 1, the 130

distance limited by the pins 99 and slots 93. When the pin 99 passes off the bevelled end of the arm 96, the springs 95 will return the jogging devices to the position shown in Fig. 1 and the cross bar or frame 33, moving onward, will engage with the block 103 on the right angled member 100 which is thus brought to the right and downward, as viewed in Fig. 1, the limit allowed by pins 102 and slots 101, and when the cross bar or beam 33 recedes, the spring 104 will return the jogging device to its normal position as shown in Fig. 1.

The device illustrated and above described for moving the belt 62 to deliver the paper is ample for most purposes, both as regards positiveness of operation and as regards distance of travel. Should it become important, however, to provide a longer travel for the paper than is possible with the device above described, I may, by securing to the bars 65 a rack 110, associated with the pulleys 61 on which the belt 62 runs, gearing 111 the last gear of which meshes with the rack 110 and provides the proper ratio between the travel of the bar 65 and the belt 62 to obtain any distance of travel desired.

The operation of my improved apparatus is as follows, it being assumed that the device is constructed and assembled as above described, and that the device has been brought into association with the front delivery press and temporarily secured there-to in any desirable manner. The press being started, as the bars 71 reciprocate and move into the position shown in Fig. 4, the cross bar or beam 33 will have been moved rearwardly until it occupies the position relative to the delivery end of the press, as indicated in Figs. 3 and 4, where the end of the lever 47 rides up on the ratchet tooth 44, rotating in this manner the shaft 37 and lifting the gripping devices 39 upwardly to provide a substantial space between the free ends thereof and the free ends of the gripping members 40. At this time, the ends of the bars 75 will engage with the forward ends of the rods 83, moving the same rearwardly and causing a kicking forward of the printed sheet 87 by the arms 81 and the jogging devices 80 so that the printed sheet is moved positively into the position shown in Fig. 6 where it will be positively engaged by the gripping devices 39 and 40. As the cross bar or beam 33 reaches its extreme rearward position, the hook end of the lever 47 rides over the end of the ratchet tooth 44, allowing the springs 41 to bring the gripping devices 39 and 40 into close association with each other and positively gripping the forward edge of the paper there-between. As the bars 71 move rearwardly toward the press, the cross bar or beam 33 with its associated parts moves forwardly,

carrying the printed paper with it and, as the paper is drawn from the press, the tapes 77 are unrolled from the shaft 76 and thus providing a rest for the paper as it leaves the tapes 67 of the press proper. The forward motion of the cross beam 33 and associated parts will continue as long as the rearward motion of the bars 71 continues and, as the cross bar or beam 33 approaches its most forward position, which will be when the printed sheet 87 is in position over the table or platform top 90 and when the roller 50 on the lever 51 rides up on, and engages the cam surface of the cam block 49. When this happens, the free end of the gripping members 40 will be depressed or moved away from the free ends of the gripping members 39, releasing the paper and as the entire apparatus associated with the cross bar or beam 33 moves rearwardly, the tapes 75 are gradually withdrawn from beneath the printed paper 87 which thereupon falls into the position on the table or platform top 90. This sequence is repeated indefinitely and, as the pile of paper gets larger and larger, the shaft 27 is rotated by means of the crank 30 to gradually lower said table or platform top or, should it be deemed desirable, I may mount on the top of the forward end member 11 a block 112 in which is secured a shaft 113, a pawl 114 being rotatably mounted on said shaft. On the shaft 27 in association with the pawl 114 is a ratchet wheel 115 while secured to the cross bar or beam 33 in threaded lugs 116 thereon is a threaded bolt or adjusting rod 117 which, as the cross beam or bar reciprocates, engages with the pawl 114 to cause a step by step rotary movement of the shaft 27 in the direction to lower the table or platform top 90.

While I have necessarily shown and described the preferred embodiments of my invention somewhat in detail, it is to be understood that I may vary the size, shape, and arrangement of parts within wide limits without departing from the spirit of the invention.

Having thus described my invention, what I claim as new is:

1. An improved portable extension delivery table for printing presses and the like, comprising a frame, castors on which said frame is mounted, a paper holding table adjustably mounted for vertical movement in said frame, and a paper feeding mechanism on said table and adapted for association with the delivery end of a printing press.

2. An improved portable extension delivery table for printing presses and the like, comprising a frame, castors on which said frame is mounted, means for vertically adjusting the table with respect to the castors, a paper receiving table mounted on said frame and adjustably mounted for vertical

movement with respect to said frame, paper feeding devices mounted on said frame, means for temporarily securing said frame to the delivery end of a printing press, means for coupling the paper feeding devices on the frame with paper feeding devices on the delivery end of a printing press, and means associated with said paper feeding devices for moving the paper holding table vertically with respect to the frame.

In testimony whereof, I have signed my name to this specification.

MORRIS J. BAILEY.
